PLIERS WITH LINK CONNECTED
HANDLE AND JAW

Arthur H. Hagen, Globe, Ariz.

Application September 17, 1945, Serial No. 616,788

8 Claims. (Cl. 81—46)

1

This invention relates to improvements in tools such as pliers.

The primary object of the present invention is to provide a pair of pliers in which a better leverage or increased pressure is obtained in gripping or clamping articles between the jaws of the tool. More specifically, the invention contemplates pliers in which one of the jaws is connected to its handle by a link pivotally connected to said jaw and handle and so arranged with respect to co-operating abutments on the two handles of the tool as to amplify the force exerted in closing the handles so that an increased pressure is exerted by the jaws when an article is to be clamped or gripped between the latter.

Another object of the invention is to provide a pair of pliers in which an article gripped between the jaws can be retained between the same without continuing the pressure used in closing the handles and jaws. In connection with this feature of locking an article in clamped position between the jaws, means are also provided for retaining said locking means inoperative so that the pliers can be used as any ordinary pair of pliers.

With these and other objects in view, the invention consists in certain details of construction and combinations and arrangements of parts, all as will hereinafter be more fully described and the novel features thereof particularly pointed out in the appended claims.

In the accompanying drawings—

Figure 1 is a plan view illustrating the pliers in their open position;

Fig. 2 is a similar view with the pliers closed on an article between the jaws;

Fig. 3 is a plan view illustrating the assembly of the jaw and handle with their interconnecting link;

Fig. 4 is a similar view of the other integrally formed handle and jaw;

Fig. 5 is an edge view of the integral jaw and handle; and

Fig. 6 is a detail sectional view on the line 6—6 of Fig. 1.

The present tool or pliers consists essentially of the two jaws 10, 11 pivotally connected together by a pivot pin 12 and the two handles 13, 14, the handle 13 being formed integrally with the jaw 10 and the handle 14 being connected to jaw 11 by a link 15 which is attached to jaw 11 by the pivot pin 16 and to the handle 14 by a pivot pin 17. Jaw 11 is formed with a rearward extension 11a and the rear end of this extension engages against the surface of a recessed portion

2

14a of handle 14 when the jaw and handles are in their opened position as shown in Fig. 1. When pressure is exerted on the handles to close the handles and jaws, a spring 20 connected to handle 14 and jaw 11 and the engagement of extension 11a with the surface 14a of handle 14 causes said jaw and handle to move as a unit until jaw 11 engages against an object or article between the jaws, whereupon the tension of spring 20 is overcome and handle 14 becomes disengaged from jaw extension 11a as indicated in Fig. 2.

As shown in Fig. 5, jaw 10 and handle 13 have an opening 21a extending therethrough in which the handle 14 is positioned. Ribs 22 are formed in this hollow portion 21 of jaw 10 and handle 13, said ribs being spaced apart for reception of the handle 14. Mounted on said handle 14 at one side of the ribs 22 are means for rendering the connecting link 15 operative to increase the pressure transmitted from handle 14 to jaw 11. As shown in Fig. 1, the pivotal connection 17 between link 15 and handle 14 and the pivotal connection 12 between the jaws 10, 11, are normally located at opposite sides of a line intersecting pivot pin 16 and the pivot pin 23 of an abutment or block 24 carried on opposite sides of the handle 14. This abutment or block 24 is adapted to engage against the ribs 22 when the handles are pressed together and the jaws 10, 11 engage an article positioned between them. For instance, when the jaws engage an article between them the tension of spring 20 is overcome by continuing the pressure on the handles whereupon the handle 14 will tend to pivot on the pivot pin 17. This action on the part of handle 14 moves the block or abutment 24 into engagement with ribs 22 whereupon the handle 14 will then tend to turn on the pivot pin 23, the block 24 at that moment being held stationary by the ribs 22. This turning movement of handle 14 on pin 23 forces the pivotal connection 17 between the handle and link toward the line AA with the result that jaw 11 is forced with greater pressure toward jaw 10. If the object gripped between the jaws will yield sufficiently under the pressure imposed on the handles of the tool the pivotal connection 17 between link 15 and handle 14 can be moved sufficiently far to pass beyond the line AA intersecting pivots 16 and 23, so that the pliers will be locked in their thus closed position until the handles are forcibly separated to return the pivotal connection 17 to that side of the line AA on which it is normally located.

As stated above, means are provided for regulating this action of the connecting link 15 and

these means consist of a stop or screw 25 carried by the link 15 and adapted to engage an extension 11a of jaw 11. By adjusting screw 25 in link 15, the movement of pivotal center 17 with respect to the line AA can be varied at will. That is by adjusting the screw 25 so that its end is comparatively close to the jaw extension 11a the movement of pivot pin 17 toward the line AA during the closing of the handles and jaws will be rather limited whereas, if the screw 25 is so adjusted that it is spaced a maximum distance from the jaw extension 11a, the pivotal connection 17 will be permitted a maximum movement, which will carry it beyond the line AA. In other words, if the stop 25 is adjusted to permit a maximum movement of the pivot pin 17 during the closing of the handles and jaws then said pin 17 will be capable of moving beyond the line AA so as to temporarily lock the jaws in closed position. This would be the adjustment of the parts when it is desired to hold an article between the jaws without continuing the application of pressure to the tool handles. On the other hand, if it is simply desired to use the tool as a pair of pliers it is only necessary to adjust stop screw 25 so that its point will come into contact with jaw extension 11a just before the pivot pin 17 comes into line with the pivot pins 16, 23, during the closing of the jaws.

What is claimed is:

1. In a pair of pliers comprising pivotally connected jaws and a handle for each jaw, a connecting link pivotally secured at its opposite ends to one of said jaws and its handle, an abutment pivotally associated with said handle, a stop on the other handle engageable by said abutment, said first mentioned handle being rotatable on the pivot of said abutment when the latter is in engagement with said stop to move the pivotal connection between said handle and connecting link toward a line intersecting the pivotal connection between said link and its jaw and the pivotal center of said abutment, and means for adjustably limiting the movement of said pivotal connection between said connecting link and handle toward said line.

2. A pair of pliers comprising a pair of pivotally connected jaws and a handle for each jaw, one handle being formed integral with its jaw, a link connecting the other jaw and the other handle, said link being pivotally attached to said other handle and jaw, an arcuate rib on the integral handle, an abutment pivoted on said other handle movable into engagement with said rib by the closing of the handles, the pivotal connections between said jaws and between said link and said other handle being normally positioned at opposite sides of a line intersecting the pivotal mounting of the abutment and the pivotal connection between said link and said other jaw, said other handle being free to turn relative to said abutment when the latter is positioned against said rib to force the pivotal connection between said link and other handle toward said line.

3. A pair of pliers comprising a pair of pivotally connected jaws and a handle for each jaw, one handle being formed integral with its jaw, a link connecting the other jaw and the other handle, said link being pivotally attached to said other handle and jaw, an arcuate rib on the integral handle, an abutment pivoted on said other handle movable into engagement with said rib by the closing of the handles, the pivotal connections between said jaws and between said link and

handle being normally positioned at opposite sides of a line intersecting the pivotal mounting of the abutment and the pivotal connection between said link and said other jaw, said other handle being free to turn relative to said abutment when the latter is positioned against said rib to force the pivotal connection between said link and said other handle toward said line, said pivotal connection between said link and said other handle being movable past said line to lock the jaws in closed position.

4. A pair of pliers comprising a pair of pivotally connected jaws and a handle for each jaw, one handle being formed integral with its jaw, a link connecting the other jaw and the other handle, said link being pivotally attached to said other handle and jaw, an arcuate rib on the integral handle, an abutment pivoted on said other handle movable into engagement with said rib by the closing of the handles, the pivotal connections between said jaws and between said link and handle being normally positioned at opposite sides of a line intersecting the pivotal mounting of the abutment and the pivotal connection between said link and said other jaw, said other handle being free to turn relative to said abutment when the latter is positioned against said rib to force the pivotal connection between said link and said other handle toward said line, and means on said connecting link engagable with said other jaw to limit the closing movement of said handles and the movement of the pivotal connection between said link and other handle toward said line;

5. A pair of pliers comprising a pair of pivotally connected jaws and a handle for each jaw, one handle being formed integral with its jaw, a link connecting the other jaw and the other handle, said link being pivotally attached to said other handle and jaw, an arcuate rib on the integral handle, an abutment pivoted on said other handle movable into engagement with said rib by the closing of the handles, the pivotal connections between said jaws and between said link and handle being normally positioned at opposite sides of a line intersecting the pivotal mounting of the abutment and the pivotal connection between said link and said other jaw, said other handle being free to turn relative to said abutment when the latter is positioned against said rib to force the pivotal connection between said link and other handle toward said line, and a stop on said link engageable with said other jaw for controlling the extent of movement of the said pivotal connection between said link and other handle toward said line.

6. A pair of pliers comprising a pair of pivotally connected jaws and a handle for each jaw, one handle being formed integral with its jaw, a link connecting the other jaw and the other handle, said link being pivotally attached to said other handle and jaw, an arcuate rib on the integral handle, an abutment pivoted on said other handle movable into engagement with said rib by the closing of the handles, the pivotal connections between said jaws and between said link and handle being normally positioned at opposite sides of a line intersecting the pivotal mounting of the abutment and the pivotal connection between said link and said other jaw, said other handle being free to turn relative to said abutment when the latter is positioned against said rib to force the pivotal connection between said link and other handle toward said line, and a stop engageable with said other jaw for controlling the extent of movement of the

said pivotal connection between said link and other handle toward said line, said stop being adjustable relatively to said other jaw to vary the extent of movement permitted said pivotal connection.

7. A pair of pliers comprising a pair of pivotally connected jaws and a handle for each jaw, one handle being formed integral with its jaw, a link connecting the other jaw and the other handle, said link being pivotally attached to said other handle and jaw, an arcuate rib on the integral handle, an abutment pivoted on said other handle movable into engagement with said rib by the closing of the handles, the pivotal connections between said jaws and between said link and handle being normally positioned at opposite sides of a line intersecting the pivotal mounting of the abutment and the pivotal connection between said link and said other jaw, said other handle being free to turn relative to said abutment when the latter is positioned against said rib to force the pivotal connection between said link and other handle toward said line, a screw threaded in said link engageable with said other jaw for controlling the movement of the pivotal center between said link and other handle toward said line, said screw being adjustable in said link toward and from said other jaw to vary the extent of movement permitted said pivotal center.

8. A pair of pliers comprising a pair of pivotally associated jaws, a handle for each jaw, one handle being formed integrally with its jaw, a connecting link pivotally attached to the other handle and jaw, a spring connected to said other handle and jaw yieldingly resisting relative movement between the same whereby said other

handle and its jaw will move as a unit on the pivotal connection between the two jaws until the resistance of said spring is overcome, a rib on the integral handle, an abutment pivoted on said other handle engageable with said rib, the pivotal connections between said jaws and said link and other handle being normally positioned at opposite sides of a straight line intersecting the pivotal connection between said other jaw and link and the pivotal mounting of said abutment, said other handle being movable on the pivotal connection between it and said link to move said abutment into engagement with said rib when the resistance of said spring is overcome by the jaws closing upon an object therebetween and said other handle being movable on the pivotal connection between it and said abutment when said abutment is in engagement with said rib to move the pivotal connection between said other handle and said link toward said line and to force said other jaw into intimate contact with an object between the jaws.
